UNITED STATES PATENT OFFICE

OWEN W. THOMAS, OF MINNEAPOLIS, MINNESOTA, ASSIGNOR TO PUFFER-HUBBARD MANUFACTURING CO., OF MINNEAPOLIS, MINNESOTA, A CORPORATION OF MINNESOTA

BOX

Application filed March 22, 1930. Serial No. 438,039.

This invention relates to new and useful improvements in boxes and more particularly to folding boxes.

An object of the invention is to provide a box comprising side and end walls suitably connected together at the corners of the box and having metallic rails secured to the lower portions of two of said walls and projecting inwardly to provide supports for the box bottom, and each rail comprising vertically disposed ears adapted to engage outer surfaces of the lower portions of said box walls and having horizontally disposed portions adapted to engage the bottom edges of the walls, and each rail further having a flange portion adapted to engage inner surfaces of the box walls and an inwardly projecting shelf adapted to provide a support for the box bottom and also means for stacking the boxes one upon another.

A further object is to provide in combination with a folding box including side and end walls and a bottom hinged to one of said side walls, a pair of metallic rails each provided with horizontally disposed portions adapted to be seated against the bottom edges of the end walls of the box, and said horizontal portions being provided on one side with vertically disposed ears adapted to engage outer surfaces of the end walls, and the opposite sides of said horizontally disposed portions having depending wall portions connected together and provided at their lower ends with shelf-like portions which project inwardly and provide supports for the box bottom, when the box is unfolded or set up, and the connecting means between said horizontally disposed portions projecting upwardly into the box and engaging the inner surfaces of the end walls and cooperating with said ears to secure the rails to the box walls in proper positions, and the relative positions of said rails upon the box walls and the lengths thereof being such as to provide means for stacking the boxes, one upon another, the rails of one box being adapted to extend downwardly into the open top of another box, thereby to retain the boxes in position, one upon another.

Other objects of the invention will appear

from the following description and accompanying drawings and will be pointed out in the annexed claims.

In the accompanying drawings, there has been disclosed a structure designed to carry out the various objects of the invention, but it is to be understood that the invention is not confined to the exact features shown as various changes may be made within the scope of the claims which follow.

In the drawings:

Figure 1 is a perspective view showing the rails provided at the lower edges of the end walls of the box and the box bottom folded inwardly;

Figure 2 is a bottom view of the box when folded;

Figure 3 is a top view of the box, when folded;

Figure 4 is an enlarged detail sectional view showing the manner of securing the rails to the lower edges of the box walls;

Figure 5 is a detail sectional view showing a means for hinging the box bottom to one of the walls of the box;

Figure 6 is an enlarged detail sectional view on the line 6-6 of Figure 4, showing the rail of one box projecting into the open top of another box, as when stacking the boxes one upon another; and

Figure 7 is a perspective view of one of the rails removed from the box.

In the selected embodiment of the invention here shown, for purposes of disclosure, there is illustrated in Figure 1, a box comprising side walls 2 and 3 and end walls 4, pivotally connected together at the corners of the box by suitable hinges. The walls at diagonally disposed corners of the box are hinged together by suitable angle plates 5 and straps 6, secured to the box walls by suitable lacing wires 7, as indicated by the dotted lines at the right hand side of Figure 1. The walls at the opposite corners of the box are hinged together by strap members 8 and 9 which also are laced to the slats constituting the box walls by suitable lacing wires 11, indicated at the left hand side of Figure 1. Portions of the lacking wires 7 and 11 are also shown in Figure 3, 4, and 6.

The walls of the box are here shown composed of a plurality of slats tied together by the lacing wires 7 and 11, as will readily be understood by reference to Figures 1 and 4.

5 The box bottom 12 is also shown composed of a plurality of slats, and is hinged to the side wall 2 by suitable hinges 13, each of which is here shown as comprising a plate 14 secured to the bottom 12 and having a hook portion 15 adapted to engage an elongated aperture provided in an angle plate 16, secured to the lower edge of the side wall 2, as best shown in Figure 5. By thus hinging the bottom 12 to the side wall 2, it may be folded 10 upwardly into the box, as shown in Figures 2 and 3 between the walls of the box. The angular shape of the hinge plates 5 at opposite corners of the box cause the end and side walls of the box to be spaced apart, 15 when the box is folded, so as to provide room between the box walls for the box bottom as best shown in Figure 3.

Another important feature of this invention resides in the construction of the rails 25 17 provided at the lower edges of the end walls 4 of the box. These rails are best shown in Figures 1 and 7, and each is provided with horizontally disposed portions 18 adapted to be seated against the lower edges 19 of the end walls 4. An upstanding ear 21 is integrally formed with each portion 18 and are shaped to engage outer surfaces of the lower slat as shown in Figures 1 and 6. Rivets 22 secure the ears 21 to the box walls, 30 35 as shown in Figures 4, 5, and 6.

The horizontally disposed portions 18 have depending vertical wall portions 24 integrally formed therewith, with which a shelf 23 is integrally formed. This shelf projects inwardly and provides a support for the box bottom 12, when the box is unfolded. The vertical wall portions 24 connecting the portions 18 with the shelf 23 are connected together by a vertical wall portion 25 having its upper marginal edge extending above the portions 18 as shown in Figure 7, and is adapted to engage the inner surface of the bottom slat of the end wall. The upper marginal portions of the walls 25 are adapted to 40 45 engage the inner surface of the lower slats of the end walls, as shown in Figure 1, thereby cooperating with the ears 21 to secure the rails to the lower edges of the end walls.

The shelf-like portion 23 extends substantially the full width of the interior of the box and is provided at its ends with upturned wall portions 26 adapted to engage inner surfaces of the upper edges of the walls of another box upon which the rails may be seated, as clearly shown in Figure 5. Projections 27 are provided at the ends of the shelves 17 to provide feet for the crate when placed upon a floor or other flat surface, as will readily be understood by reference to Figures 1 and 4.

60 65 65 The outer surfaces of the vertically disposed

wall portions 24 of each rail 17 lie substantially in the plane of the inner surface of each end wall, so that when one box is placed upon the top of another box, the rails 17 of the top box will project into the lower box 70 and will thereby provide means for stacking the boxes, one upon another, and retain them in such position.

It will thus be seen that the rails 17 provide means for supporting the box bottom 12 when the box is in unfolded operative position, and they also provide means for stacking the boxes and retaining them in such position, and, in addition, provide runners for the box when in open position. Each rail and the means provided thereon for engaging the lower portion of the box wall, is integrally formed from a single piece of metal, thereby providing a rugged rail construction and one which may be manufactured at a minimum cost.

I claim as my invention:

1. The combination with a box comprising a bottom and side and end walls suitably connected together at the corners of the box, of metallic rails secured to the lower portions of two of said walls, each of said rails including vertically disposed portions adapted to engage outer surfaces of a box wall and horizontally disposed portions adapted to be seated against the bottom edge of a wall, and each having a depending inwardly extending shelf adapted to provide a support for the box bottom.

2. The combination with a box comprising a bottom and side and end walls suitably connected together at the corners of the box, of metallic rails secured to the lower portions of two of said walls, each of said rails including spaced apart vertically disposed ears adapted to engage outer surfaces of a box wall and horizontally disposed portions adapted to be seated against the bottom edges of the walls, and each having a depending inwardly extending shelf adapted to provide supports for the box bottom.

3. The combination with a box comprising a bottom and side and end walls suitably connected together at the corners of the box, of metallic rails secured to the lower portions of two of said walls, each of said rails including spaced apart ears adapted to engage outer surfaces of a box wall and horizontally disposed portions adapted to be seated against the bottom edges of the walls, and each rail having a portion adapted to engage an inner surface of a box wall and a depending inwardly extending shelf-like portion adapted to provide supports for the box bottom.

4. The combination with a foldable box comprising hinged together side and end walls and a hinged bottom, of metallic rails secured to the lower portions of the end walls, each of said rails having an upstanding ear at each end thereof adapted to engage outer sur-

- faces of the end walls, horizontally disposed portions connected with said ears and adapted to be seated against the bottom edges of the walls, a vertical wall portion connected with 5 the horizontally disposed portions of each rail and adapted to engage inner surfaces of said end walls, and a depending shelf-like portion connected with the horizontally disposed and vertical portions of each rail, said 10 shelf-like portion extending inwardly to provide supports for the box bottom when the box is open.

5. The combination with a folding box comprising hinged together side and end 15 walls and a bottom hinged to one of said side walls, of a metallic rail secured to the lower edge of each end wall and each having horizontally disposed portions adapted to be seated against the bottom edges of said end walls, 20 ears integrally formed with said horizontally disposed portions and adapted to engage outer surfaces of the box walls, means for securing said ears to the box walls shelf-like portions integrally formed with said horizontally 25 disposed portions and extending downwardly and inwardly to provide supports for the box bottom, the overall length of said rails being substantially equal to an inside dimension of the box whereby the rails of one box 30 may be inserted into the open top of another box to provide means for stacking the boxes, one upon another.

6. A rail for a foldable box comprising horizontally disposed portions adapted to 35 be seated against the bottom edge of a box wall, ears on said horizontally disposed portions adapted to be engaged with surfaces of the box wall, means whereby said ears may be secured to the box wall, substantially vertically 40 disposed portions integrally formed with said horizontally disposed portions and depending therefrom, a shelf-like portion integrally formed with said vertically disposed portions and positioned to provide a support 45 for a box bottom, an upright wall portion interposed between said vertically disposed portions and having an edge projecting above said horizontally disposed portions and spaced from said ears, the spacing between 50 said ears and said projecting edge being substantially equal to the thickness of the box wall, and the overall length of said rail being substantially equal to an inside dimension of the box.

55. 7. A rail for a foldable box comprising horizontally disposed portions adapted to be seated against the bottom edge of a box wall, ears on said horizontally disposed portions adapted to be engaged with surfaces of the 60 box wall, means whereby said ears may be secured to the box wall, substantially vertically disposed portions integrally formed with said horizontally disposed portions and depending therefrom, a shelf-like portion integrally formed with said vertically disposed

portions and projecting laterally therefrom to provide a support for a box bottom, an upright wall portion interposed between said horizontally disposed portions and having an edge projecting above said horizontally disposed portions and spaced from said ears, the spacing between said ears and said projecting edge being substantially equal to the thickness of the box wall, said shelf-like portion having upturned terminal flanges, and the 70 overall length of said rail being substantially equal to an inside dimension of the box, whereby said upturned terminal flanges may engage inner surfaces of the box walls.

In witness whereof, I have hereunto set my 80 hand this 15th day of February, 1930.

OWEN W. THOMAS.
